UNITED STATES PATENT OFFICE.

CHARLES OSBORNE, OF NEW YORK, N. Y., ASSIGNOR TO WHITING MANUFACTURING COMPANY, OF NEW YORK, N. Y., A CORPORATION OF NEW YORK.

DESIGN FOR A HANDLE FOR SPOONS OR SIMILAR ARTICLES.

SPECIFICATION forming part of Design No. 36,143, dated November 18, 1902.

Application filed September 20, 1902. Serial No. 124,255. Term of patent 14 years.

To all whom it may concern:

Be it known that I, CHARLES OSBORNE, a citizen of the United States, residing in the city of New York, borough of Manhattan, in the 5 county and State of New York, have invented a new, original, and ornamental Design for Handles for Spoons or Similar Articles, of which the following is a specification, reference being had to the accompanying drawings, 10 forming part thereof and showing the design applied to a spoon.

Figure 1 is a view of the obverse, and Fig. 2 a view of the reverse, face.

The leading feature of my design is the 15 shape of the head and shank with the decoration thereon composed of foliate ornaments, in which the flowers, buds, leaves, and stems of the lily predominate and form the chief characteristic. On each side of the shank at 20 its junction with the bowl is a drooping leaf curving to the latter, and between them on the obverse face is an open lily-flower, from which rises a lily-stem with alternately-placed leaves terminating in a lily-bud. The shank 25 widens slightly immediately above the bud and bears an open lily, the stem of which disappears amid the leaves below. The head shows a plain central field and bears on each side a gracefully-curved leafed stem following 30 the contour of the head and terminating one in a full-blown lily-blossom and the other in a bud lying partly upon the petals of the blossom. Above the latter is another open lily, forming the tip or termination of the head. On the reverse 35 face the shank is less-elaborately orna-

mented and is bordered with reeds, broken at intervals by scrolls and conventional leaves, leading to the swell below the head, at which point is a centrally-placed lily-bud flanked by its leaves. From foliated ornaments on 40 each side of the bud extends a leafed stem following the outline of the head, with a narrow open field between, and terminates in open lily-flowers lying partially one upon the other. From the pair thus positioned extends 45 a short central stem bearing two oppositely-placed leaves and a full-blown lily-blossom located just below the extreme tip of the head, which is finished with a shell ornament flanked by scrolls which form the outline of 50 the head from the tip to the shank, excepting as the contour is broken by the lily-leaves.

The ornamentation on both faces is in high relief and presents a particularly graceful and pleasing effect.

55

It will be understood that the design may be applied to articles in all classes of table flat ware.

I claim—

The ornamental design for a handle for 60 spoons or similar articles, herein shown and described.

In testimony that I claim the invention above set forth I affix my signature in presence of two witnesses.

CHARLES OSBORNE.
